(57) CLAIM

The ornamental design for a LED inspection light, as shown and described.

DESCRIPTION

FIG. 1 is a perspective view of my LED inspection light;

FIG. 2 is a front view of FIG. 1;

FIG. 3 is a back view of FIG. 1;

FIG. 4 is a rear perspective view of FIG. 1;

FIG. 5 is a side view of FIG. 1; and,

FIG. 6 is an opposite side view of FIG. 1.

The broken lines are included to show a feature that forms no part of the claimed design.
